(57) **CLAIM**

The ornamental design for a display screen with graphical user interface, as shown and described.

DESCRIPTION

FIG. 1 is a front view of the first image in a sequence for a display screen with graphical user interface showing my new design;

FIG. 2 is a second image thereof;

FIG. 3 is a third image thereof; and,

FIG. 4 is a fourth image thereof.

The appearance of the transitional image sequentially transitions between the images shown in FIGS. 1. The process or period in which one of the images transitions to another forms no part of the claimed design.

The outermost broken line illustrates a display screen or portion thereof and forms no part of the claimed design. The remaining broken lines, including all of the figure icons and the broken line squares immediately adjacent to the figure icons, illustrate portions of the graphical user interface and form no part of the claimed design.
